UNITED STATES PATENT OFFICE.

WILLIAM C. NEWELL, OF PORTLAND, OREGON.

AUTOMATIC HEAT-CONTROLLED CUT-OUT.

1,309,908.

Specification of Letters Patent. Patented July 15, 1919.

Application filed June 27, 1917. Serial No. 177,413.

To all whom it may concern:

Be it known that I, WILLIAM C. NEWELL, a citizen of the United States, residing in the city of Portland, county of Multnomah, 5 and State of Oregon, have invented certain new and useful Improvements in Automatic Heat-Controlled Cut-Outs, of which the following is a specification.

My invention relates to automatic heat-controlled cut-outs, and more particularly to a device adapted to operate automatically, under a given temperature, for the purpose of opening the switch which controls the electric current which is developing the heat, 15 and while my invention is capable of adaptation to a great many different uses, and in different places, in order to illustrate the same, I have shown it as embodied in an electrically heated flat iron, which I will 20 now describe.

In the drawings,—

Figure 1 is a side elevation of a flat iron with parts broken away and shown in section in order to show the application of my 25 invention thereto;

Fig. 2 is a vertical, sectional view through my invention as here embodied; and

Fig. 3 is a vertical sectional view through my improved cut-out.

Fig. 4 is a cross sectional view taken on line 4—4 of Fig. 3.

Broadly considered, my invention comprises a movable member with means for moving the same, said means being held 35 against action by another member, the release of which is controlled by a fusible metal, adapted to fuse under a certain degree of heat, whereby to permit the release of said member, said member being adapted 40 to be held in its operating position each time by the congealing of said fusible metal. In other words, the fusing of a fusible metal, under an increased heat operates to release a movable member, which operates, for example, to break an electric circuit developing 45 the heat, whereupon said fusible metal under the reduced heat again congeals and said movable member is again set and held to be automatically released by another 50 fusing of said metal.

One of the principal objects of my invention is to provide in a device of the character referred to a member having therein a cavity filled with a fusing metal, whereby 55 said metal can be repeatedly and alternately

fused and congealed as the heat to which it is subjected varies.

Another object of my invention is to provide in combination with a cavity, or pocket, filled with a fusing metal, a movable trip, or holding, member adapted to be released by the fusing of the metal around the same, with means for automatically moving said trip, or holding, member into its operating position relative to said pocket, or cavity, whereby it will be there held by the congealed metal around the same.

Referring now more in detail to the drawings, 1 designates an electric flat iron having therein heating coils 2, and the terminal 70 posts 3 and 4. These form no part of my invention other than a means for illustrating the practical application thereof for controlling the electric circuit by means of which said iron is heated.

My invention as here embodied comprises a cylindrical body 5, having in its opposite inner walls vertical guideways 6—6, and provided at its lower end with feet 7—7, by means of which said body is mounted upon 80 the bottom of the flat iron 1, as shown. Mounted in the top of said body 1, is a hollow bearing member 8, through which operates a plunger-rod 9, the lower end of which is secured to a piston 10, having therein a 85 cavity or pocket 11, adapted to be filled with a fusible metal 12, which is held in said pocket, or cavity, by means of a screw plug 13. Slidably mounted through said piston 10, and through said cavity 11, and the fusible 90 metal 12, therein, is a steel pin 14, preferably roughened or knurled at its middle portion, as at 15, whereby to facilitate the adherence of the fusible metal 12 thereto when it is congealed. Said movable pin 14 constitutes a trip, or holding, member, adapted 95 when it is centered, and when said piston 10 is in its down position, to underlie a toe 16, upon the lower end of a spring 17, mounted upon the side of the body 5, said holding toe 15, projecting through an aperture 18, in the side of said body 5.

Mounted on said plunger 9, within the hollow bearing member 8, is an abutment disk 19, against which bears the upper end 105 of a coiled spring 20, the lower end of which bears upon a screw disk 21, screwed into the lower end of said hollow bearing member 8, as clearly illustrated in Fig. 3. A conical shaped contact collar 22, is mounted 110

on said plunger 9, above the disk 19, and is insulated from said plunger 9, as indicated. Said contact collar 22 is adapted when in its down position to contact with 5 two opposed terminal screws 23-23, to which circuit wires 24-24 are connected, said circuit wires being adapted to form a part of the main circuit for heating the coils 2-2, in said iron.

10 The operation of my device may be briefly described as follows:

With the parts set in the positions shown in Fig. 3, the contact collar 22 engages and connects the terminal screws 23-23, so that 15 the circuit is closed and the coils 2-2 are being heated. Should the iron become overheated, the metal 12 in the pocket, or cavity, 11, formed in the piston 10, fuses, and the holding pin 14, is released and moved to 20 the right under the tension of the spring 20, which moves the plunger 9 and the piston 10 upwardly, said holding pin 14, being forced to the right by the cam action between its left-hand end and the holding toe 16. 25 The guideway 6, in the right-hand side of the body 1, is slightly enlarged, opposite the right-hand end of the holding pin 14, as at 6', to permit said pin to be moved to the right sufficiently to allow its left-hand end 30 to move upwardly past the holding toe 16. As the piston 10 moves upwardly, however, said pin 14, is automatically moved back to a centered position by the inclined portion 6^a, of said guideway. This upward movement of the plunger 9 opens the circuit by 35 moving the contact collar 22, out of engagement with the terminal screws 23-23. The circuit being opened, the iron commences to cool and the metal 12, in the cavity, or 40 pocket, 11, again congeals and the holding pin 14 is thereby again held, or locked, in its centered position.

In the present embodiment of my invention, it is necessary, in order to again establish the circuit through the terminals 23-23, 45 to press the plunger 9 downwardly to its position as shown in Fig. 3, whereupon the left-hand end of the holding pin 14 flexes the holding toe 16, outwardly sufficiently to 50 pass downwardly by it, whereupon said holding rod 14 and the piston 10 will be again held in their down position by the holding toe 16. Thus every time the iron becomes overheated the fusing metal 12 is fused, the 55 holding pin 14 is released and moved so as to pass the holding toe 16, as the piston 10 is moved upwardly under the tension of the spring 20, which raises the plunger 9, and opens the circuit by raising the contact collar 22. Said plunger 9, is provided with a 60 press button 9', whereby it can be conveniently pressed downwardly to again establish the heating circuit.

I am aware that many changes in details 65 can be made in my invention as here em-

bodied for purposes of illustration, and I do not, therefore, limit my invention to this particular showing, except as I may be limited by the hereto appended claims.

I claim:

1. In a device of the character referred to, two elements movable adjacent each other, means normally acting to move one of said elements, a latch member projecting through one of said elements into latching engagement with the other of said elements, and a fusible material around said latch member in the element through which it projects, holding it against movement through said element, whereby when said fusible material 80 fuses said latch member is released to move bodily through the element carrying the same and out of engagement with the other element, substantially as described.

2. In combination, a movable member having a pocket therein, means normally operating to move the same, a fusible metal in said pocket, and a holding member movably mounted through said pocket and adapted to be held against movement by said fusible metal when the same is congealed, and to be released for movement when said metal fuses.

3. In combination, a cylindrical member, a piston movable therein and provided with a pocket, a spring normally operating to move said piston, a fusible metal in said pocket, and a holding member movably mounted through said pocket and said fusible metal and adapted to be moved out of holding position when said fusible metal fuses under increased heat, whereby to release said piston.

4. In combination, a cylindrical member, a piston movable therein and provided with a pocket, a spring normally operating to move said piston, a fusible metal in said pocket, a holding member movably mounted through said pocket and said fusible metal and adapted to be moved out of holding position when said fusible metal fuses under increased heat, whereby to release said piston, and means for automatically moving said holding member back to its holding position relative to said piston.

5. In a device of the character referred to, two elements mounted one within the other and movable relative to each other, means normally acting to move said inner element relative to the outer member, a latch member carried by the inner member and adapted for holding it against movement within the outer member, a fusible material within the inner member and around said latch member for holding it against movement relative to the inner member and means for said latch member to catch with, substantially as described.

6. In combination a fixed member, a movable member having a pocket therein, a latch

member carried by said movable member and movable relative thereto and adapted to have latch action to prevent movement of said movable member, and a fusible material in said pocket for holding said latch member against movement relative to said movable member and securing it thereto, whereby when said fusible material fuses under heat, said latch member moves relative to the member which carries it and permits the movement of said movable member, substantially as described.

7. In a device of the character referred to, in combination, an outer member, a movable inner member, a spring adapted to move said inner member, said inner member being provided with a pocket, a fusible metal in said pocket, a holding member movably mounted through said inner member and said pocket and adapted to be held against movement by the congealing of said metal and to be released for movement by the fusing of said metal, a spring catch member adapted to be engaged by said holding member, substantially as described.

8. In a circuit controlling device, a latch member movable in opposite directions, a member carrying the same, a fusible material for holding said latch member against movement relative to the carrying member, and a yielding means positioned to be engaged by said latch member and to be moved thereby when said latch carrying member is moved adjacent thereto, substantially as described.

9. In a device of the character referred to, in combination, a fixed contact, a movable

contact, a spring adapted to normally move said movable contact out of engagement with said fixed contact, and means for holding said movable contact in engagement with said fixed contact against the tension of said spring, said means comprising a member movable with said movable contact member and provided with a pocket, a fusible metal in said pocket, a holding member through said pocket and said fusible metal and adapted to be held against movement by said metal when congealed and to be released when said metal fuses, and a yielding catch member adapted to be engaged by said holding member, substantially as shown and described.

10. In a circuit controlling device, a casing, a latch carrying member therein, a latch member carried thereby and movable relative thereto, a fusible material for holding said latch member against movement relative to the latch carrying member, a yielding member positioned to be engaged by said latch member to move the latter as said latch carrying member is moved adjacent thereto when said fusible material fuses, and means on said casing wall for engaging and moving said latch member to its normal position in said latch carrying member as the latter moves upwardly, substantially as described.

Signed at Portland, Multnomah county, Oregon, this 22nd day of June, 1917.

WILLIAM C. NEWELL.
